United States Patent

Des. 237,171
Patented Oct. 14, 1975

237,171

PALETTE

Frances Tyler Norman, 3832 Olympia Drive,
Houston, Tex. 77019

Filed Feb. 14, 1974, Ser. No. 442,500

Term of patent 14 years

Int. Cl. D19—06

U.S. Cl. D19—35

Fig.1.

Fig.2.

Fig.3.

FIG. 1 is a top plan view of a palette showing my new design;

FIG. 2 is a front elevational view; and

FIG. 3 is a cross-sectional view taken along line 3—3 of FIG. 1.

I claim:

The ornamental design for a palette, as shown and described.
